UNITED STATES PATENT OFFICE.

FREDERICK V. D. LONGACRE, OF YONKERS, NEW YORK, ASSIGNOR TO THE INGERSOLL-RAND COMPANY, OF JERSEY CITY, NEW JERSEY, A CORPORATION OF NEW JERSEY.

VALVE.

1,354,318.

Specification of Letters Patent. Patented Sept. 28, 1920.

Application filed August 9, 1919. Serial No. 316,364.

To all whom it may concern:

Be it known that I, FREDERICK V. D. LONGACRE, a citizen of the United States, residing at Yonkers, in the county of Westchester and State of New York, have invented a certain new and useful Improvement in Valves, of which the following is a specification.

This invention relates to a valve adapted to be used for compressors, vacuum pumps, etc., and in particular to a multiported valve of the annular type adapted to improve the efficiency and construction of a valve of the plate type. Furthermore, the invention relates to improvements in the type of valve disclosed in the patent to Breinl, No. 1,244,286 granted October 23, 1917. Particularly the invention is adapted for the valves, either inlet or discharge, for compressors for air or other gases, but may also be used with advantage in water pumps.

The objects of my invention are to provide a valve of the annular plate type which will be simple, compact and efficient in operation and one that will provide, when in its open position, a continuous path for the fluid without abrupt corners or edges and will permit the fluid to pass through the valve with the least amount of resistance and in continuous stream line paths, approaching as closely as possible perfect flow with minimum change in pressure and with minimum resistance. A further object of the invention is to provide an annular plate valve suitably shaped on the side that engages the valve seat which will permit the valve to seat in a manner similar to a puppet valve, and one which will remain fluid tight indefinitely. A still further object of the invention is to suitably design the passages for the fluid, which is usually air, through the valve seat and also past the valve and through the cover plate that will guide the fluid without eddies or undue frictional resistance, so that the fluid passing through the valve plate and cover plate will be guided in continuous stream line paths. In other words, the fluid in passing through the valve from the time it passes the seat plate until it passes away from the cover plate is guided by the contours of the valve seat, the valve plate and cover plate, with the minimum changes in direction and is maintained in parallel con-

tinuous streams in the same manner as the 55 passage of fluid through an adiabatic nozzle, the velocity of the fluid first gradually increasing until the fluid reaches the throat after which the velocity decreases again as the fluid passes the outer limits of the 60 valve.

With these and other objects in view, my invention consists in the features of construction and operation set forth in the following specification.

In the drawings annexed hereto and forming a part hereof:

Fig. 1 shows a cross sectional view through the central line of a valve made in accordance with the present invention 70 taken in the line 1—1 of Fig. 2;

Fig. 2, a top plan view of the complete valve.

Fig. 3, a cross sectional view of the complete valve when in open position, along 75 the line 1—1 of Fig. 2;

Fig. 4, another form of the valve made in accordance with my invention, adapted to act as an inlet valve, in open position.

Fig. 5, a plan view of one form of guide 80 plate and spring arm;

Fig. 6, a cross-sectional view of the same;

Fig. 7, a plan view of the valve plate;

Fig. 8, a cross-sectional view of the same; and

Fig. 9, an isometric view of the valve plate, guide plate and spring showing these parts spaced somewhat apart.

Referring more particularly to the drawings, the numeral 1 refers to the wall of a 90 compressor cylinder suitably bored to contain a valve. Reference numeral 2 refers to the valve seat adapted to be inserted within the opening in the cylinder wall of a compressor in the usual manner. Above 95 seat plate 2 is cover plate 3, held in position against the valve seat by a suitable stud 4 and nut 5. Lugs 6 extending from the periphery of the cover plate 3 press against the outer edge of seat 2, thus aiding in holding the valve firmly to its seat. The valve plate is shown at 7 and is made as clearly shown in Fig. 1, of suitably forged or shaped material so that it extends somewhat within the passages 8 provided in the 100 valve seat, and seats against the valve seat 2 in a manner similar to a puppet valve, that is, it presses against the seat 2 on either

side of the passages 8 at an angle rather than on two narrow flat surfaces as in the patent referred to above.

The dished or contoured shape of the valve 7 enables the central portion of the valve to extend considerably into the passages 8 of the valve seat 2, thus lessening to a considerable degree the amount of clearance space in the valve seat. In the open 10 position of the valve as shown in Fig. 3, the contour of the valve plate 7 forms walls which in conjunction with the contoured walls of the valve seat 2 form the multiple-ports or passages for the fluid which will permit as near as possible stream line flow and a minimum resistance.

While I have shown the valve 7 of material of uniform thickness and suitably forged or pressed in the shape as shown in 20 figures of the drawing, I wish it to be understood that the upper surface of the valve may be flat or of any other convenient shape and still be within the spirit of the invention as expressed in the claims. The valve seat 2 at and near its passages 8 is suitably contoured as shown at 9 and 10 so that fluid passing through the valve seat is guided in stream like paths when the valve is in its open position. The points or narrow lines 30 upon which the valve contacts with the seat are two concentric circles passing through points 11 and 12 in Fig. 1 which form part of the contour of the valve seat 2 and do not produce any sharp corners or sudden changes in direction of the fluid, this contact being at points near inner and outer points in the transverse section of the valve plate 7. The cover plate 3, furthermore, is suitably contoured as shown at 13 and 14 so 40 that the fluid after passing the valve plate is still guided in paths free from abrupt corners or abrupt changes in direction, and the fluid after passing the throat of the passages at the valve 7 is guided and its velocity is reduced again to normal.

In order to hold the valve 7 in its seated position, spiral springs 15 are provided, in the modification shown, two of these springs being shown, suitably contained in a cavity 50 16 provided in the cover plate 3. At the point where the springs 15 join the valve plate 7 the contour of the valve plate is somewhat modified, forming a raised portion 17 around which the valve spring 15 is adapted to fit. In addition to the valve spring 15 the valve plate is also provided with suitable spring arms as shown at 18. These may be parts of a guide plate 22 secured about the stud 4 between the seat 2 60 and cover plate 3 at one end, the other or outer end being secured beneath the spring 15 and surrounding the raised portion 17 in the manner above described.

Preferably the end of the spring arms 18 65 of the guide plate 22 is suitably contoured

as clearly shown in Fig. 6, the part 19 fitting easily about the raised portion of the valve 17.

It will be seen from the above that no riveting or welding is required to hold the 70 end 18 of the guide plate 22 in contact with the valve plate 7 as this is accomplished by the parts being formed as above described. With the parts assembled as shown the spring 15 firmly holds the valve plate and 75 guide plate in operative position.

If desired an additional or supplementary spring may be provided on the spring arms 18. These are shown at 20 in Figs. 5 and 6. At one end they are attached to the arms 80 18 by means of rivets or other fastening means 21. These supplementary springs 20 are slightly offset from the arms 18 so that during the opening of the valve 7 they will gradually be compressed between the arms 85 18 and the hollow in the upper part of the valve 7, thus aiding in the cushioning of the movement of the valve 7.

In operation as the valve 7 is opened and closed the arms 18 act to position and retain the valve 7 properly in alinement with the valve seat 2 and also act while the valve is opening as a means to cushion its action. This cushioning action occurs in the following manner; the recessed portion of the 95 valve 7 as it moves upwardly comes into closer and closer connection with the arms 18 and it thus gradually forces the air trapped between the arms 18 and the valve 7 to be expelled. This forcing of the air 100 from the recessed portion producing a slightly increased resistance to the opening of valve 7 especially when it approaches its fully opened position, thus aiding in cushioning the valve.

Furthermore, the contact of two convex surfaces produces a construction of minimum initial line contact and therefore permits the valve to wear to a minimum sustaining seat, requisite to any condition of 110 operation to which the valve may be applied, and which condition can vary, in different applications. This function is of extreme value under different temperature conditions of operation. Also, in case of 115 variation in operation temperature of the valve and seat. The minimum initial contact surface, permits the valve to wear automatically to its correct tight bearing surface for the varying conditions of temperature and pressure to which it may be applied.

The modification illustrated in the drawings has but one annular ring, but it is obvious that a number of annular plate valves 125 7 may be assembled in one complete valve, the valves being of different diameters grouped concentrically about the stud 4, each of the valve plates being suitably guided by a single guide plate having spring 130

arms connected with equally spaced points of each of the valves, or if desired, each annular section may be provided with its own independent guide plate and arms.

5 Referring now to the modifications shown in Fig. 4, it is obvious from the drawing that the valve structure is similar but is inserted in the cylinder wall in reverse position so that the valve is adapted to act as an inlet valve. The valve plate in this modification is in every other way similar to that shown in Figs. 1 and 3 the only changes being the changes in the seat 2 necessary for this part to be inserted in the cylinder wall in the reverse position. It will be noted upon examination of Fig. 3 that with the valve plate in its open position, continuous stream line paths are provided for the inrushing fluid.

It is to be understood that the present showing and description disclose only one specific embodiment of my present invention, and that other forms and modifications are included within the spirit and scope thereof, as expressed in the appended claims.

25 What I claim is:

1. In a multi-ported valve for fluid compressors or pumps, a valve seat, a cover plate held in position against the valve seat, an annular valve plate having its seat engaging surface convexly contoured and extending partly within the passage in the valve seat, said valve plate having a limited movement between said seat and cover plate, and said valve seat, valve plate and cover plate being adapted to permit a continuous stream line flow of fluid entirely through the multi-ports of the valve.

2. In a multi-ported valve for fluid compressors or pumps, a valve seat, a cover plate held in position against the valve seat, and a valve plate adapted to seat as a puppet valve on narrow lines of contact along both sides of the passage in said valve seat and within the passage, said valve plate having a limited movement between said valve seat and cover plate.

3. In a multi-ported valve for fluid compressors or pumps, a valve seat, a cover plate held in position against the valve seat, and an annular valve plate adapted to seat as a puppet valve on narrow lines of contact along said passage in both sides of the valve seat and within the passage, said valve plate having a limited movement between said valve seat and cover plate.

4. In a multi-ported valve for fluid com-

pressors or pumps, a valve seat, a cover plate held in position against the valve seat, and an annular valve plate having a limited parallel movement between said valve seat 60 and cover plate, said valve plate seating as a puppet valve on narrow lines of contact along both sides of the passage in said valve seat and within the passage and being adapted when in its open position to permit 65 a continuous stream line flow of fluid through the multi-ports of the valve.

5. In a valve for fluid compressors or pumps, a valve seat, a cover plate, a valve plate having a limited movement between 70 said valve seat and cover plate, and a guide member having spring arms detachably engaging the valve plate without rubbing contact at equally spaced points therein.

6. In a valve for fluid compressors or 75 pumps, a valve seat, a cover plate, a valve plate having a limited movement between said valve seat and cover plate, a guide member having spring arms detachably attached at equally spaced points in said 80 valve, said spring arms being provided with supplementary spring arms engaging a surface of the valve.

7. In a multi-ported valve for fluid compressors or pumps, a valve seat, a cover 85 plate held in position against the valve seat and provided with at least one passage, and an annular valve plate having a limited parallel movement between said valve seat and cover plate, the walls of the said valve 90 seat, the contour of the valve plate and the walls of the passage in the cover plate being so shaped that when the valve is in open position the fluid is guided so that it may pass completely through said passages and 95 valve plate in stream lines without abrupt turns or the formation of eddy currents and with gradual change in velocity.

8. In a multi-ported valve for fluid compressors or pumps, a valve seat having convex seating surfaces, a cover plate held in position against the valve seat to limit the movement of the valve plate, and a valve plate having its seat engaging surface convexly contoured whereby a minimum initial 100 line contact is obtained between the valve and its seat, permitting the valve to automatically wear to a minimum sustaining seat.

In testimony whereof, I have hereunto set 110 my hand.

FREDERICK v. D. LONGACRE.
